C. A. DUNHAM

RADIATOR TRAP

Filed Sept. 4, 1923

UNITED STATES PATENT OFFICE.

CLAYTON A. DUNHAM, OF GLENCOE, ILLINOIS, ASSIGNOR TO C. A. DUNHAM COMPANY, OF MARSHALLTOWN, IOWA, A CORPORATION OF IOWA.

RADIATOR TRAP.

Application filed September 4, 1923. Serial No. 660,839.

My invention relates to radiator traps of the type employing a flexible disk thermostat for controlling the escape of the water of condensation, and has for its principal object 5 the provision of a new and improved form and arrangement of parts for connecting the valve to the disk. In devices of this type in which it is important that the valve shall work with the greatest possible efficiency 10 so as to avoid the loss of steam from the radiator, it is of course essential that the valve be capable of seating promptly and accurately so as to completely close the valve opening. To this end, and in order to offset, 15 so far as possible, the bad effect of foreign matter becoming lodged between the valve and its seat, I have sought to provide a construction by reason of which there shall be a maximum of efficiency, which construction 20 may be strong and durable, and which shall be simple and comparatively inexpensive to manufacture.

The preferred means by which I have accomplished my several objects are illustrated in the accompanying drawing and are hereinafter specifically described. That which I believe to be new and desire to cover by Letters Patent is set forth in the claim.

In the drawing:—
30 Fig. 1 is a central vertical section through a trap equipped with my improved construction.

Fig. 2 is an enlarged detail view, being a vertical cross section through the parts by 35 which the valve is mounted upon the thermostatic disk.

Fig. 3 is a perspective view upon an enlarged scale, showing the socket member to which the valve is to be connected; and

40 Fig. 4 is a view similar to Fig. 2, but showing a modified form of construction.

Referring to Figs. 1 to 3, in which corresponding parts are indicated by the same reference characters, 10 indicates a casing member forming the body portion of the casing of my improved trap, the casing being completed by means of a cap 11 secured by means of screw threads to the body portion 10. The casing is provided with an inlet port 12 and an outlet port 13, a web 14 being interposed between the inlet and outlet ports, such web being provided with a valve opening 15.

A thermostatic disk 16 of any approved

type is secured by means of a stem 17 upon 55 the lower face of the cap 11, the disk 16 being preferably in centered position with respect to the opening 15 in the web 14. The thermostatic member 16 is of any approved diaphragm type adapted to expand upon 60 the application of heat thereto, being preferably provided with a quantity of volatile liquid for causing the desired expansion, as is well understood in the art. In the construction shown, the lower diaphragm is indicated by the numeral 18, as is shown in Fig. 2.

Depending from the diaphragm 18 of the thermostatic disk 16, there is a valve 19 in the form of a plate in position opposite the valve opening 15 so as to close the opening 15 upon the expansion of the thermostatic disk 16 under the influence of heat. In the improved construction here shown, the valve 19 is mounted upon the diaphragm 18 by 70 means of a ball and socket joint, by which the valve plate 19 is adapted to rock vertically with respect to the diaphragm 18, but is held against vertical movement otherwise with respect to the diaphragm 18, whereby 80 the valve 19 is caused to move vertically with the central portion of the diaphragm 18. In the construction shown, the ball and socket joint comprises a ball 20 formed on the valve plate 19, having a snug working 85 fit in a socket 21 formed in the lower face of a socket member 22 which extends through a central opening in the diaphragm 18. Those faces of the socket 21 with which the ball contacts when moved to operative 90 position comprise cylindrical side walls 26 and an upper conical wall 27. The conical portion 27 keeps the ball centered in the socket, and also allows only line contact of the ball with the walls of the socket. 95 This reduces friction, allowing movement of the valve plate and insuring a substantially perfect fit of the valve plate upon its seat. The pockets 28, not occupied by the ball, provide spaces wherein any foreign matter 100 entering the socket may be displaced which will prevent binding of the parts. A collar 23 surrounds the upper end of the socket member 22 upon the upper face of the diaphragm 18, the parts being rigidly secured 105 together by soldering or in any other suitable manner. In the construction shown in Fig. 4, the upper end of the socket member

22 is riveted over the upper end of the collar 23. The head 20 of the valve 19 is preferably held in position in the socket 21 by the inwardly directed edge of the socket member which is formed of comparatively thin metal and is turned by a spinning process into position for retaining the ball in position with a working fit in the socket.

In order to facilitate a close fit between 10 the valve plate 19 and the web 14 around the valve opening 15, the seat for the valve is made rounding, as at 24. By reason of the valve 19 being mounted rockingly in position, a snug seating is insured, so that it is 15 not necessary that the contact of the valve with its seat extend over a considerable area. As will be readily understood, by rounding the seat as above explained, the likelihood of foreign matter becoming lodged between 20 the seat and the valve, is very materially lessened. Furthermore, the likelihood that such foreign matter shall be loosened in a short time is very materially increased.

While I prefer to employ the construction 25 and arrangement as shown in the drawing and as above described, it will be understood that I do not wish to limit myself to the details of such construction, except so far as such detailed construction is specifically 30 claimed, inasmuch as it is evident that various changes might be made in the construc-

tion without departing from the spirit of my invention.

I claim:—

A radiator trap comprising a casing having inlet and outlet ports, a valve opening arranged in the casing between the inlet and outlet ports, there being an annular valve seat at the inlet end of the valve opening having a rounded valve-engaging surface, 35 a hollow thermostatic disk comprising a pair of flexible diaphragms connected at their outer peripheral edges, the upper diaphragm being centrally adjustably mounted within the casing, whereby the disk is rigidly 40 mounted opposite the valve opening with capacity for movement only toward or from the valve-seat in response to temperature changes, a socket member having a reduced portion fitting within a central opening in 50 the lower diaphragm, a collar secured to this reduced portion within the disk, and a valve plate adapted to engage the valve seat when the disk is expanded, there being a ball member on the upper face of the plate 55 fitting within the socket with capacity for universal movement therein, the lower edge of the socket member being inturned about the ball to prevent disengagement of the ball and socket.

CLAYTON A. DUNHAM.
